Primary Examiner—Ruth McInroy**Attorney, Agent, or Firm—George A. Bode****[57] CLAIM**

The ornamental design for a cycling helmet having air filtering and breathing means, as shown and described.

DESCRIPTION

FIG. 1 is a left side elevational view of a cycling helmet having air filtering and breathing means showing my new design;

FIG. 2 is a right side elevational view thereof;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a bottom perspective view thereof, the person shown in broken lines is for illustrative purposes only and forms no part of the claimed design.

FIG. 3FIG. 1FIG. 2

FIG. 6FIG. 5FIG. 4

FIG. 7
